BOOM AND BUCKET DISTRIBUTING APPARATUS FOR CONCRETE MIXERS

Charles F. Ball, Wauwatosa, and Louis G. Hilke-meier, Milwaukee, Wis., assignors to Chain Belt Company, Milwaukee, Wis., a corporation of Wisconsin

Application June 26, 1939, Serial No. 281,299

8 Claims. (Cl. 104—92)

The invention relates to boom and bucket distributing apparatus for concrete mixers, and has for its principal object to provide improved mechanism for accomplishing reciprocatory traverse of the bucket along the boom, and for raising and lowering the latter.

It is now almost universal practice to equip concrete mixers of the paving type with mechanism for distributing the mixed concrete discharged from the mixing drum over areas of considerable extent. Such mechanism commonly comprises a horizontally disposed boom of from twenty to thirty five feet or more in length, having one end suitably pivotally mounted adjacent the discharge opening of the mixing drum for both horizontal and vertical swinging movements, and a receptacle or bucket mounted on such boom for reciprocating travel from and to said discharge opening. The outer end of the boom is supported by a block and tackle extending from the boom to the main frame of the mixer, by means of which the boom may be raised and lowered in a vertical plane about its horizontal pivot. The bucket, which may hold a complete batch of a cubic yard or more of mixed concrete, is usually reciprocated on the boom at the will of the operator by means of cables which are power driven in various ways from the engine or motor which drives the mixing drum, and one of the prime objects of the present invention is to provide improved means for actuating these cables.

The swinging movements of the boom in the horizontal plane occur quite frequently in the normal operation of placing concrete pavement, and are usually accomplished through the use of manually controlled power drives, such for example, as that disclosed and claimed in our co-pending application filed June 26, 1939, Serial No 281,298 entitled Boom swing mechanism for concrete mixers. On the other hand, pivotal movement of the boom upwardly or downwardly in a vertical plane is necessary only at infrequent intervals, and while such movement may be accomplished by manually operable means, still because of the weight of the parts it is preferable to also actuate the boom elevating and lowering devices by power. The present invention therefore contemplates the provision of means whereby the raising and lowering mechanism may be actuated by power at the volition of the operator through a simple connection to the drive mechanism for the bucket cables.

Briefly, the cable drive mechanism of the present invention comprises a pair of constantly

driven oppositely running sprockets or gears, each having a clutch, preferably of the friction type, associated with it, and means under manual control of the operator for actuating the clutches whereby the sprockets or gears may be optionally clutched one at a time to a driven shaft. The said shaft is arranged to drive a winding drum for the bucket cables through another clutch, which may be of the double jaw type, adapted in one position to transmit power to said drum and in another position to transmit power, preferably through an irreversible worm drive, to a spool upon which the boom raising and lowering cable is wound. The bucket operating cables are so wound upon their drum that upon rotation of the latter in a given direction, one cable will be unwound while the other will be simultaneously wound thereon, taking the place of the cable which is leaving; and the said cables pass over suitable pulleys or sheaves mounted upon the frame of the mixer and upon the boom, whereby they are guided to the bucket, to which they are each attached. The drum also has means associated with it whereby rotation of the drum will cause axial travel of the same, thereby always maintaining the entering and leaving points of the cables upon the drum in substantial alignment with the adjacent sheaves about which they pass.

Knockouts are also provided arranged to automatically disengage the main driving clutches as the bucket reaches either end of the boom, and a brake is also associated with the clutch shaft, having control means whereby it is automatically released whenever either main clutch is engaged and automatically applied whenever both clutches are disengaged. Thus the bucket will be quickly stopped as either main clutch is disengaged, and will be positively held by the driving cables in whatever position it may occupy whenever both clutches are disengaged.

Since it requires more power to move the loaded bucket outwardly from the mixer than it does to return it after being emptied, the out-drive clutch is preferably of heavier construction than the in-drive clutch, and may conveniently take the form of a multiple disk clutch, whereas the in-drive clutch may be of the single or double plate type.

With the above and other features in view which will appear as the description proceeds, the invention comprises the novel details of construction and combinations and arrangements of parts more fully hereafter disclosed and particularly pointed out in the appended claims.

Referring to the accompanying drawings form-

ing a part of this specification, in which like reference characters designate like parts in all the views:

Figure 1 is a diagrammatic side elevational view, partly broken away, of the discharge end of a paving concrete mixer equipped with a boom and bucket distributing apparatus, and showing one form of bucket operating and boom elevating mechanism constructed in accordance with the present invention applied thereto;

Fig. 2 is an enlarged elevational view of the mechanism constituting the invention, as seen from the left of Fig. 1;

Fig. 3 is a still further enlarged longitudinal vertical sectional view of the right hand portion of the mechanism shown in Fig. 2, showing the driving sprockets, their associated main clutches and the control instrumentalities therefor, the driven shaft, the brake and a portion of its control means; the out-drive clutch being shown engaged, and the brake released;

Fig. 4 is an enlarged transverse sectional view, taken approximately on the plane indicated by the line 4—4 of Fig. 2, looking in the direction of the arrows, showing the brake in applied position;

Fig. 5 is an enlarged detail sectional view of a portion of the brake control mechanism, taken on the plane indicated by the line 5—5 of Fig. 4, looking down;

Fig. 6 is a view similar to Fig. 3 and on the same scale, of the central portion of the apparatus shown in Fig. 2, illustrating the bucket cable winding drum, the means for producing axial movement thereof, and a portion of the main clutch knockout mechanism;

Fig. 7 is a transverse sectional elevational view, taken on the plane indicated by the line 7—7 of Fig. 6, looking in the direction of the arrows;

Fig. 8 is a view similar to Fig. 7, taken on the plane indicated by the line 8—8 of Fig. 6; and

Fig. 9 is a horizontal sectional view of the left hand portion of the apparatus illustrated in Fig. 2, taken approximately on the plane indicated by the line 9—9 in said figure, showing the spool for the boom raising and lowering cable, the drive mechanism therefor, and the double clutch for selectively connecting the drive to either the bucket cable winding drum or the boom cable spool.

Referring more particularly to Fig. 1 of the drawings, there is shown the discharge end of a typical paving mixer which may comprise a frame having the horizontal members 15, 16, vertical members 17 and a transverse member 18. The said frame is mounted upon crawler treads 19 and has the mixing drum 20 mounted within it upon suitable supporting rollers 21. The said drum is provided with the usual axial discharge opening 22, see Fig. 2, which may be surrounded by a drip ring 23, through which the mixed concrete is discharged by means of suitable discharge chute members 24 into a distributing bucket 25. This bucket is mounted for reciprocating movements upon a boom 26 by means of a carriage or trolley 27 and is adapted to be moved inwardly and outwardly along the boom by the out-drive cable 28 and the in-drive cable 29, all as may be readily understood by those skilled in the art. The said cables are trained about sheaves 18^a fixedly mounted on the frame member 18, and 26^a mounted on the boom 26, the peripheries of which sheaves are substantially tangent to the plane of the axis of the vertical pivot 31 of the boom.

The end of the boom adjacent the mixer is pivotally mounted as at 30 for vertical swinging movements of the boom and as at 31 for horizontal swinging movements of the same, which horizontal movements may be accomplished through the medium of a worm wheel 32 and an associated worm, not shown, which may be driven by suitable power means 33 here shown as being of the type described and claimed in our co-pending application Serial No. 281,298 referred to above.

The raising and lowering movements of the boom 26 about its pivot 30 are accomplished by a block and tackle mechanism which includes the elevating and lowering cable 34 and the bucket traverse inwardly and outwardly on the boom is accomplished through the mechanism constituting the present invention which is generally indicated at 35. As fully set forth in our said co-pending application, power for accomplishing the horizontal swinging movements of the boom through the mechanism 33 is derived from the main power plant of the mixer through a drive from the mixing drum 20 which comprises a ring gear or sprocket 36, chain 37 engaging therewith and a sprocket 38 carried by the drive shaft 39 of the boom swinging mechanism 33. As is also fully disclosed in our said co-pending application, the boom swinging mechanism 33 includes a pair of oppositely driven sprockets 40 and 41 which serve as driving means for the bucket operating mechanism and boom raising and lowering mechanism constituting the present invention.

Referring now more particularly to Figs. 2 to 5 of the drawings, the bucket traverse mechanism comprises a shaft 45 which is journaled by a ball or other anti-friction bearing 46 in a bearing bracket 47 rigidly mounted upon the frame members 16 and 18. The said shaft has journaled upon it spaced sprocket wheels 48 and 49 about which are trained the chains 50 and 51 respectively, which also engage the sprockets 40 and 41 respectively, of the boom swinging mechanism 33, whereby the said sprockets 48 and 49 are constantly driven in opposite directions. The sprocket 48 constitutes the in-drive power transmission and has associated with it clutch annuli or members 52 (see Fig. 3) carrying suitable clutch facings 53 and operatively connected to the sprocket by means of pins or studs 54 to compel rotation as a unit and yet permit axial movement of members 52 for accomplishing their clutching function and to allow for wear of facings 53. A brake drum 55 is rigidly secured to the shaft 45 adjacent the sprocket 48 and together with the pressure ring 56, constitutes the driven element of the in-drive clutch inasmuch as the clutch annuli 52 carried by the sprocket 48 are arranged to be optionally clamped between the flat faces of the ring 56 and of the drum 55 as will be readily understood. The engaging and disengaging movements of the clutch annuli are accomplished through the said pressure ring 56 which is mounted upon a clutch hub 57 rigidly secured to shaft 45. The ring 56 is axially movable on the said hub by means of the clutch fingers 58 operable through links 59 by the shifting collar 60 which in turn is axially movable by the shifting lever 61 which engages with the pins 62 of the shifting yoke 63.

The out-drive sprocket 49 also has a friction clutch associated with it comprising the bell 65 carrying the driving clutch disks 66 arranged

in co-operative relation with the driven clutch disks 67 which are carried by the hub 68 keyed or otherwise rigidly secured upon the shaft 45. Frictional engagement between the disks 66 and 67 is accomplished through a pressure ring 69 slidably mounted upon an extension of the hub 68 and movable by the clutch fingers 70 which are operable through links 71 from the clutch collar 72 which in turn is reciprocated by means of the operating lever 73 which engages with the pins 74 carried by the clutch operating yoke 75. Release springs 76 of any ordinary or usual construction may be included to secure disengagement of the clutch elements 66 and 67 as will be readily understood.

Since the bucket 25 when filled with a batch of mixed concrete amounting to a cubic yard or more requires considerably more power in its outward movements along the boom than it does during its inward movement after the concrete has been discharged, the out-drive clutch just described is preferably of heavier construction than the in-drive clutch comprising the annuli 52, brake drum 55, and the pressure ring 56.

As best shown in Figs. 3 and 4 a pair of brake shoes 76 are pivotally hung as at 77 in the bearing bracket 47 and surround the outer circumference of the brake drum 55. These shoes are normally urged into engagement with the said drum 55 by springs 77 mounted upon the rod 78 and the pressure of which may be suitably adjusted by the adjusting nuts 79. The shoes are normally in frictional contact with the brake drum whenever the two clutches are disengaged so that the shaft 45 will be positively held against rotation at such time. However, as either clutch is moved to engaging position by its lever 61 or 73, and the parts associated therewith, the brake will be released by the following mechanism:

Pivotaly mounted upon the extension 80 of the housing of the boom swing mechanism 33 is a pair of levers 81 the upper ends of which are crossed as clearly indicated in Fig. 4, and are engaged by adjustable stop screws 82 carried by the lower ends of the brake shoes 76. By adjustment of the said screws 82, wear of the brake lining may be compensated, as will be readily understood. The lower ends of the levers 81 have rollers 83 journaled upon them which rollers are alined with a rod 84, the ends of which are adjustably connected by eye-bolts 86 to the lower ends of the clutch operating levers 61 and 73. The said rod 84 is provided with a pair of oppositely disposed recesses 85 into which the rollers 83 may move when the clutch operating levers 61 and 73 are in neutral position and such movements of the rollers into the recesses will cause the levers 81 to permit the springs 77 to cause engagement of the brake shoes 76 with the periphery of the brake drum 55, as will be readily understood. However, whenever the clutch operating levers 61 and 73 are moved to engage one or the other of the main driving clutches the rod 84 will be likewise moved to bring the recesses 85 out of alinement with the rollers 83 subjecting the latter to the full diameter of the rod 84 and causing a rocking of the levers 81 about their pivots whereby their upper ends will cause a spreading of the brake shoes against the action of springs 77 and disengagement of the brake lining from the periphery of the drum 55. Thus as either clutch is engaged the brake will be released and the shaft 45 will be free to be driven by one or the other 75

of the sprockets 48 and 49. The eye-bolts 86 at either end of the rod 84 permit adjustment of the parts to secure proper initial relationship of the brake and clutches, and also permit of compensation for alterations in the relationship of the shifting levers 61 and 73 as the clutches are taken up for wear.

The rod 84 is provided with a stud 87 which is engaged by one arm of a lever 88 (see Fig. 2), another arm of which is provided with an operating handle 89 by means of which the operator may shift the rod 84 and clutch operating levers 61 and 73 to produce engagement of either the in-drive or out-drive sprocket with the shaft as desired.

The shaft 45 is provided at its left hand end, as viewed in Fig. 3, with a suitable coupling member 90 which engages a companion coupling member 91 (see Fig. 6) carried by a shaft 92. 20 This shaft is journaled in bearings 93 carried by a tubular shaft 94 which surrounds the shaft 92 and is journalled in suitable anti-friction bearings 95 carried by bearing brackets 96 and 97 supported by the frame members 16 and 18. A winding drum 98 is freely mounted upon the tubular shaft 94 for longitudinal sliding movements thereon and the inner periphery of the drum is provided with a pair of longitudinal keyways 99 which slidably receive keys 100 carried at the outer ends of the arms of a driving member 101 which is keyed or otherwise rigidly secured to the tubular shaft 94. The outer periphery of the drum 98 is provided with a helical groove 102 for the reception of the out-drive cable 28 and the in-drive cable 29 which cables are wound upon the said drum in opposite directions as is common in the art, whereby as one cable is unwound from the drum through the rotation of the latter, the other cable will be wound thereon taking the place of that portion of the cable which is leaving.

Inasmuch as the sheaves or pulleys on the mixer frame over which the cables pass after they leave the drum are fixed, and since the entering and leaving points of the cables upon the drum is constantly shifting longitudinally of the latter as the cables are wound and unwound, provision is made according to the present invention to shift the drum axially as it is rotated so as to maintain the entering and leaving points of the cables upon the drum in substantially constant planes whereby the cables may be fed to and taken from the frame carried sheaves in substantial alinement therewith, and cable strain and wear prevented. As here shown, the means for producing axial movement of the drum 98 comprise a screw 103 rigidly connected to one end of the drum and engaged by a relatively fixed nut 104. This nut carries an upstanding arm 105 which non-rigidly engages a bracket member 106 mounted upon the frame member 18 whereby rotation of the said nut is prevented. The said nut is also connected by means of a pair of links 107 (see Figs. 2, 7 and 9) with the fixed bearing bracket 96 which links prevent axial movement of the nut 104 while nevertheless permitting of limited transverse movement of the latter as does also the non-rigid connection between the arm 105 and the bracket 106. The nut is thus arranged to accommodate itself to alinement with the shaft 94 while at the same time rotation and axial movement of the nut are prevented.

A rod 108 is slidably mounted at one end (see Fig. 2) in a depending extension 109 of the bearing bracket 96 and the other end of the said rod

is pivotally connected as at 110 to the clutch operating lever 61. The rod 108 rigidly carries a pair of adjustable knockout arms 111 which extend upwardly and embrace the tubular shaft 94, the said arms being so located upon the rod 108 as to be engaged by the hub of the right end plate of the drum 98 or by the end of the screw 103 respectively as the drum 98 approaches the limit of its axial movement in either direction. Upon such contact the drum will move the engaged arm 111 together with the rod 108 in whichever direction the drum happens to be traveling, and the arrangement is such that this movement of the rod 108 communicated to the clutch operating levers 61 and 73 will disengage the clutch which at that time is engaged and transmitting power to the drum, whereby rotational and axial movement of the drum will be stopped and overrunning thereof prevented.

As best shown in Figs. 2 and 9, the winding spool 112 for the boom raising and lowering cable 34 is mounted upon a shaft 113 journalled in a bracket and housing 114 secured to a frame member 18. Said shaft 113 carries a worm wheel 115 which is engaged by an irreversible worm 116 carried by a shaft 117 which is in axial alignment with the shafts 92 and 94. The tubular shaft 92 has keyed to its left hand end, as viewed in Figs. 2 and 9, a clutch member 118 which is arranged for engagement with companion clutch elements formed on the right hand face of a shiftable clutch member 120 which is splined upon the shaft 92. The left hand face of the said member 120 is also provided with clutch elements arranged for engagement with companion elements carried by a clutch member 119, which may be journaled upon the end of shaft 92, and which may also constitute one element of a flexible coupling, the other element 125 of which is keyed on the shaft 117. The shiftable clutch member 120 is arranged to be moved axially upon the shaft 92 by a shifting yoke 121, which in turn is actuated by a lever 122 and a link connection 123 from a hand lever 124 located at the opposite side of the machine adjacent the operator's station. As here shown these clutches may be of the jaw type and when in the position shown in Fig. 9 the shaft 92 will not be transmitting power to either the shaft 94 or to the shaft 117, but the normal position is of course such that the driving clutch member 120 is in engagement with the driven clutch member 118 on the shaft 94 so that the latter shaft may drive the winding drum 98 as above described. However, when it becomes necessary or desirable to elevate or lower the boom 26 the clutch member 120 will be shifted through its mechanism 121, 122, 123 and 124 to disengage the driven clutch member 118 and to engage the member 119, whereupon the shaft 92 will transmit power to the shaft 117, worm 116, worm wheel 115, spool shaft 113 and spool 112, whereby the boom elevating and lowering cable 34 will be wound upon or unwound from the spool 112 to raise or lower the boom 26, as will be readily understood.

As above indicated, the boom is only raised or lowered infrequently and normally the clutch member 120 will be out of engagement with the clutch member 119 and in engagement with the clutch member 118.

While one form of the invention has been illustrated and described it is obvious that those skilled in the art may vary the details of construction as well as the precise arrangement of parts without departing from the spirit of the

invention and therefore it is not wished to be limited to the above disclosure except as may be required by the claims.

What is claimed is:

1. In a concrete mixer having a frame, a mixing drum mounted therein, a boom pivoted on said frame for horizontal swinging movements, sheaves carried respectively by said frame and boom adjacent said boom pivot, a distributing bucket mounted on said boom for traverse thereon, cables connected to said bucket and passing around said sheaves, cable-operating mechanism comprising a winding drum for said cables, mounted on said frame for rotary and axial movements, the latter in a plane substantially parallel to the axis of said frame-carried sheaves; means for rotating said winding drum in either direction at will; a screw carried by said winding drum; a nut engaging said screw; and means floatingly connecting said nut to said frame against rotation and axial movement while providing for movement thereof transversely of the axis of the screw; said screw and nut causing axial traverse of the winding drum as it is rotated to maintain the entering and leaving points of the cables on such drum in alignment with the frame-carried sheaves.

2. In a concrete mixer having a frame, a mixing drum mounted therein, a boom vertically pivoted on said frame adjacent the discharge end of said drum, sheaves carried by said frame adjacent said vertical pivot, a distributing bucket mounted for traverse on said boom to and from the discharge end of said drum, cables passing around said sheaves and connected to said bucket for causing said traverse thereof, cable-operating mechanism comprising a winding drum for said cables mounted on said frame intermediate said sheaves and the end of said mixing drum, with its axis horizontal and transverse to that of the latter, and substantially parallel to that of said sheaves; means for rotating said winding drum in either direction at will; a screw carried by said winding drum; a nut engaging said screw; pivoted links connecting said nut with the frame, for preventing axial movement of the nut while providing for movement thereof transversely of the screw axis whereby the nut may align itself with the screw; and an arm carried by the nut and engaging the frame, providing for said transverse movement of the nut while preventing rotation thereof.

3. In a concrete mixer having a frame, a mixing drum mounted therein, a boom pivotally mounted on said frame for horizontal swinging movements, sheaves carried by said frame adjacent the boom pivot, a distributing bucket mounted for traverse on the boom to and from the discharge end of said drum, cables passing around said sheaves and connected to said bucket for causing said traverse thereof, operating mechanism for said cables comprising a shaft journaled transversely of said frame adjacent said boom pivot; constantly-operating, oppositely-running driving members journaled on said shaft; a normally applied brake carried by the shaft preventing rotation thereof; a cable winding drum carried by said shaft for rotational and axial movements; means for causing said axial movements of the winding drum as it is rotated, whereby to maintain the entering and leaving points of the cables on such drum in alignment with said sheaves; manually operable control means for alternatively connecting said driving members to said shaft and releasing said brake

approximately simultaneously with the connection of either; and means engageable by said winding drum as it approaches its limits of axial travel, connected to said control means to automatically cause the latter to disconnect the connected driving member and to re-apply the brake.

4. In a concrete mixer of the type having a mixing receptacle provided with a discharge opening, a boom extending from adjacent said opening, a material-receiving bucket mounted on said boom for traverse to and from said opening, and actuating cables for said bucket, means for causing traverse of said bucket along said boom in either direction at will, comprising a rotatable, axially fixed shaft; means for alternatively driving said shaft in either direction; a winding drum about which said cables are trained, splined to said shaft for rotation therewith and axial movement relative thereto; a screw-threaded member carried by said drum; and a relatively fixed nut engaged by said threaded member, whereby rotation of the drum in either direction by said shaft will cause axial movement of the drum relative to the shaft and maintain the entering and leaving points of the cables in substantially constant planes as they are wound upon and unwound from the drum.

5. In a concrete mixer of the type having a mixing receptacle provided with a discharge opening, a boom extending from adjacent said opening, a material-receiving bucket mounted on said boom for traverse to and from said opening, and actuating cables for said bucket, means for causing traverse of the bucket along the boom in either direction at will, comprising a tubular shaft; a winding drum about which said cables are trained, splined to said tubular shaft for rotation therewith and axial movement relative thereto; a screw-threaded member rigid with said drum; a relatively fixed nut engaged by said threaded member, whereby rotation of said drum in either direction by the shaft will cause axial movement of the drum thereon and maintain the entering and leaving points of the cables on the drum in substantially constant planes as they are wound upon and unwound from the drum; a second shaft mounted within said tubular shaft; means for alternatively driving said second shaft in either direction at will; and means for making and breaking a driving connection between the two shafts at will.

6. In a concrete mixer of the type having a mixing receptacle provided with a discharge opening, a boom extending from adjacent said opening, a material-receiving bucket mounted on said boom for traverse to and from said opening, and actuating cables for said bucket, means for causing traverse of the bucket along said boom in either direction at will, comprising a shaft; means for alternatively driving said shaft in either direction; a winding drum about which said cables are trained, splined to said shaft for rotation therewith and axial movement thereon; a nut surrounding said shaft, said nut being mounted for movements transversely of the shaft axis but being held against rotation and longitudinal

movement; and a threaded sleeve carried by said drum, surrounding said shaft and engaging said nut, whereby rotation of the drum in either direction by the shaft will cause axial movement of the drum and maintain the entering and leaving points of the respective cables on the drum in substantially constant planes as they are wound thereon and unwound therefrom.

7. In a concrete mixer of the type having a frame, a mixing receptacle provided with a discharge opening, a boom extending from adjacent said opening, a material-receiving bucket mounted upon the boom for traverse to and from the opening, and actuating cables for said bucket, means for causing traverse of the bucket along the boom in either direction at will, comprising a shaft; means for alternatively driving said shaft in either direction; a winding drum about which said cables are trained in opposite directions, splined to said shaft for rotation therewith and axial movement thereon; a nut surrounding said shaft; connections between said nut and the frame for preventing rotation and longitudinal movement of the nut while providing for its movement transversely of the shaft axis, whereby it may accommodate itself to the alinement of the shaft, said connections including a link pivotally connected to the frame and to the nut for preventing its longitudinal movement, and a member carried by the nut engaging the frame to prevent its rotation while providing for its movement transversely of the shaft axis; and a threaded sleeve carried by the drum, surrounding said shaft and engaging the nut, whereby rotation of the drum in either direction by the shaft will cause axial movement of the drum and maintain the entering and leaving points of the respective cables upon the drum in substantially constant planes as they are wound thereon and unwound therefrom.

8. In a concrete mixer of the type having a frame, a mixing receptacle provided with a discharge opening, a boom extending from adjacent said opening, a material-receiving bucket mounted upon the boom for traverse to and from the opening, and actuating cables for said bucket, means for causing traverse of the bucket along the boom in either direction at will, comprising a tubular shaft; a winding drum about which said cables are trained in opposite directions, splined to said shaft for rotation therewith and axial movement thereon; a threaded sleeve rigid with said drum and surrounding said shaft; a nut engaging said sleeve; connections between said nut and the frame for preventing its rotation and longitudinal movement while providing for its movement transversely of the shaft axis; a second shaft mounted co-axially within said tubular shaft; means including a pair of constantly operating oppositely running clutch members, and companion clutch members alternatively engageable therewith, for alternatively driving said second shaft in either direction at will; and clutch means for making and breaking a driving connection between said shafts,

CHARLES F. BALL.
LOUIS G. HILKEMEIER.
